DESIGN FOR A HANDLE

Frank C. Wallace, North Hollywood, Calif., assignor to Monogram Manufacturing Company, Los Angeles, Calif., a corporation of California

Application September 28, 1945, Serial No. 122,385

Term of patent 14 years

(Cl. D10—8)

To all whom it may concern:

Be it known that I, Frank C. Wallace, a citizen of the United States and resident of the city of North Hollywood, county of Los Angeles, State of California, have invented a new, original, and ornamental Design for Handle, of which the following is a specification, reference being had to the accompanying drawing, forming a part thereof, in which:

Fig. 1 is a perspective view of a handle, showing my new design;

Fig. 2 is a side view;
Fig. 3 is a bottom plan view;
Fig. 4 is a top plan view; and
Fig. 5 is an end elevational view thereof.

I claim:

The ornamental design for a handle, substantially as shown.

FRANK C. WALLACE.
